UNITED STATES PATENT OFFICE.

RUSSELL PARKER, OF BROOKLYN, NEW YORK, ASSIGNOR TO PARKER, STEARNS & COMPANY, OF BROOKLYN, NEW YORK, A CORPORATION OF NEW YORK.

GARMENT-SUPPORTER.

1,265,243.

Specification of Letters Patent.

Patented May 7, 1918.

Application filed December 14, 1917. Serial No. 207,100.

To all whom it may concern:

Be it known that I, RUSSELL PARKER, a citizen of the United States, residing at Brooklyn, in the county of and State of New York, have invented certain new and useful Improvements in Garment-Supporters, of which the following is a specification.

The present invention relates more particularly to the buttons or stud members of 10 hose supporters and like devices which are embraced by a metallic loop or similar element for clasping and gripping the hose or other article to be secured.

In that type of device which is made 15 wholly of rubber stock these studs or buttons must be quite hard and firm, and of course tough. It is also desirable in some instances to make them in the form of a unitary structure, and to provide not only 20 a securing base, but a head, the base and head being joined by the loop-engaging part or shank. Difficulty, however, has been experienced in making this type of device, because of the inability to remove the same 25 from the iron molds without a prohibitive loss in breakage.

One of the primary objects of the present invention is to provide a button having the desirable characteristics, and at the same 30 time so formed that it may be removed with ease from the mold, thus obviating the above-mentioned difficulty.

An embodiment of the invention that is at present considered the preferable one is 35 illustrated in the accompanying drawings, wherein:—

Figure 1 is a perspective view of the button,

Fig. 2 is an end elevation of the same,

Fig. 3 is a horizontal section.

Fig. 4 is a plan view of the die,

Fig. 5 is a detail section of said die, illustrating the form of the mold, and also making clear how the article can be removed 45 therefrom.

Fig. 6 is a detail view in elevation of the button and coöperating loop therefor, and

Fig. 7 is a similar view, but with the head removed.

Similar reference numerals designate corresponding parts in all the figures of the drawings.

In the embodiment illustrated, the button

is a single piece, consisting of a relatively thin base 6 of rubber that is reinforced by 55 fabric, as shown at 7. Projecting outwardly from the central portion of this base is a loop-engaging portion in the form of a shank or post 8 and integral with said base. The outer end of the shank or post is provided with a flange constituting a head 9, the main part of which overhangs the base on opposite sides of said shanks, being of greater thickness than the same. The lower end 10 of this head also overhangs the base 65 and is spaced therefrom. The upper end extends along the top-side of the said shank, as illustrated at 11, being disposed on a curve, and being integrally joined to the base. 70

It will be understood that this button may be secured in the usual manner by its base 6 to the supporter, the inturned end 11 of the head being uppermost. A loop will thus effectively coöperate with the head to 75 clasp and hold a garment, and the outstanding post or shank will thus not only properly coöperate with the loop, but is reinforced by the upper end 11 of the flange or head. 80

The form of the mold obviously corresponds to the shape of the button or stud, and as shown in Figs. 4 and 5, the said mold has a shank-forming portion 8^a, an enlarged head-forming portion 9^a below the same, 85 and at one end of the shank-forming portion the opening is enlarged as illustrated at 11^a to produce the inturned portion 11 of the head or flange. Consequently when the article is formed therein, it can be easily 90 removed, inasmuch as the main body of the head 9 can be slipped out of the enlarged portion 11^a, and thus removed from beneath the inset portions that produce the shank. 95

Coöperating with the button is a clasp in the form of a loop 12 preferably constructed of sheet metal, said loop having a transverse slot 13 at one end for the reception of the elastic and having an elongated opening for the reception of the button. This opening 100 consists of an upper enlarged portion 14 of sufficient size to permit the free passage of the head therethrough. Extending from this enlarged portion is a contracted part 15 of sufficient size to receive the shank, but of 105 less width than the head. Oppositely dis-

posed notches 16 are formed adjacent to the juncture of the enlarged portion 14 and contracted portion 15, these notches receiving the upper inturned end of the head as will be clear by reference to Fig. 7.

While I prefer to employ a loop of the kind illustrated and above described, it is also possible to employ loops of other kinds.

I claim as my invention:—

- 10 1. A hose supporter button comprising a base and a loop-engaging part, the latter having a flange spaced at one end from the base and having its other end connected to said base.
- 15 2. A hose supporter button having a loop-engaging shank, a head at the outer end of the shank, and a reinforcing flange at the upper side of the shank and wider than

the same, said flange extending inwardly from the head.

3. The combination with a button comprising a base, a loop-engaging shank and a flanged head carried by the outer end of the shank and extending along one end of the same to the base, of a loop coöperating with the button and having an opening, said opening having a portion of sufficient size to permit the passage of the head, and a portion of less size for the reception of the shank, said latter portion having oppositely extending notches adapted to receive the portion of the button head at one end of the shank.

In testimony whereof, I have hereunto subscribed my name.

RUSSELL PARKER.
